UNITED STATES PATENT OFFICE.

STEVEN STEFANKO, OF GLEN CARBON, PENNSYLVANIA.

DESIGN FOR A SEALED POSTAL CARD.

58,637.

Specification for Design.

Patented Aug. 2, 1921.

Application filed July 13, 1920. Serial No. 396,025. Term of patent 7 years.

To all whom it may concern:

Be it known that I, STEVEN STEFANKO, a citizen of Hungary, residing at Glen Carbon, in the county of Schuylkill and State of Pennsylvania, have invented a new, original, and ornamental Design for a Sealed Postal Card, of which the following is a specification, reference being had to the accompanying drawing, forming part thereof.

The figure is a perspective view of a "sealed postal card" showing the new design.

I claim:

The ornamental design for a "sealed postal card" as shown.

STEVEN STEFANKO.
